UNITED STATES PATENT OFFICE.

GEORGE ULETT, OF WALTHAM, MASSACHUSETTS.

HOUSEHOLD-TOOL.

No. 857,320.

Specification of Letters Patent.

Patented June 18, 1907.

Application filed March 19, 1906. Serial No. 306,766.

To all whom it may concern:

Be it known that I, GEORGE ULETT, a citizen of the United States, residing in Waltham, county of Middlesex, and State of Massachusetts, have invented an Improvement in Household-Tools, of which the following description, in connection with the accompanying drawings, is a specification, like letters on the drawings representing like parts.

10 This invention has for its object the production of a novel household tool adapted for lifting from milk-jars, cans or bottles the usual paper sealing disk.

Figure 1 in perspective shows a household tool embodying my invention in one good form; Fig. 2 shows the top of a milk-jar with the prong thrust through the disk; Fig. 3 shows the tool turned one fourth around to cause the prong to contact with the under side of the disk; Fig. 4 is a section on the line $x-x$; and Fig. 5 is a section of Fig. 3 in the line $x'-x'$.

Referring to the drawing, A represents a handle suitably bored to receive the tang of a 25 metallic bar B, the outer end of which is made to project laterally from the side of the bar to form a point B' that is sharpened. The blade is shown as curved at its edge that bears on the top of the jar D as the tool is 30 turned one-fourth around, as will be described.

In using the tool, it will be so held in the hand that the point B' will be directed downwardly and this point is thrust through the 35 paper disk C, as represented in Figs. 2 and

4, until the flat side of the blade contacts with the upper end of the jar D. This done, the handle and blade are turned from the positions, Figs. 2 and 4, into the positions Figs. 3 and 5, where it will be seen that one 40 edge of the point B' is brought upwardly in contact with the under side of the cap, as best shown in Fig. 5, when the tool will be lifted, taking the cap with it from the mouth of the jar. The cap, when crowded into the 45 jar to seal the same is sustained on the shoulder d.

Having fully described my invention, what I claim as new and desire to secure by Letters Patent is:—

50 In a tool for household use, a handle, a connected flat blade having its outer end bent at a substantial right angle from said blade and pointed to be thrust through a paper sealing disk, the penetration of said 55 point being arrested by the blade striking the top of the jar containing said sealing disk, the subsequent rotation of said blade while resting on the top of the jar causing the side of the pointed end to be brought upwardly to contact with the under side of said sealing disk that the same may be lifted 60 positively from the mouth of the jar.

In testimony whereof, I have signed my name to this specification, in the presence of 65 two subscribing witnesses.

GEORGE ULETT.
